UNITED STATES PATENT OFFICE.

LEWIS WILLIAMS, OF JOHNSTOWN, PENNSYLVANIA, ASSIGNOR TO
CAMBRIA IRON COMPANY, OF SAME PLACE.

APPARATUS FOR ANNEALING WIRE.

SPECIFICATION forming part of Letters Patent No. 312,417, dated February 17, 1885.

Application filed August 24, 1883. (No model.)

To all whom it may concern:

Be it known that I, LEWIS WILLIAMS, a citizen of the United States, residing at Johnstown, in the county of Cambria and State of Pennsylvania, have invented certain new and useful Improvements in Apparatus for Annealing Wire, of which the following is a full, clear, and exact description.

In the drawings, Figure 1 is a section through an annealing pot or oven, showing my improvements; and Fig. 2 is a top view of the same.

The parts of the oven are indicated as follows: *a* is the brick-work or masonry. *d* is the annealing-pot. *b* is a fire-arch. *c c* are flues leading from the fire-arch to space around the pot. *h h* are floor-plates covering the masonry. *f* is the cover of the annealing-pot. *g* is a hole through the cover. *i* is a plate covering the charging-hole in the floor-plates, provided with an orifice, *p*. *k* is a flue secured to cover *i*, the continuation of which flue, *n*, is secured to the floor-plate *h*, the further continuance of this flue to connect with a general draft flue or chimney being indicated by *o*. *r* being a hole through the floor-plates. *m* is a peep-hole through which to ascertain the condition of the wire, and *l* is a ring by which the covering-plate *i* and its attached flue are hinged.

The operation of this apparatus is as follows: The coverings *i* and *f* being removed, the pot *d* is filled with wire and covered with the lid *f*. The plate-covering *i*, with its attached flue *k*, is placed in position, covering the hole in the floor-plates, connection being made between the parts of the flue *k* and *n* by

inserting the one into the other, or otherwise. This allows the heat and smoke to pass around the annealing-pot, and thence through the flues *40 k, n, and o* to the general flue or chimney.

It will be found convenient in practice to connect the flue *o* leading from each pot with a general flue passing along or between a row or rows of ovens and leading into a chimney. *45*

The plate *i*, with its attached flue *k*, are strongly made of iron, and a crane may be conveniently used in shifting them.

I am aware that an annealing-furnace has been constructed with covering-plate and flues, *50* as these are essential parts in certain forms of ovens, and that gases have been taken off centrally through the covering-plate; but my apparatus differs in making the flue *k* fast upon the covering-plate *i*, and removable with it, *55* and connecting removable flue *k* with permanent flue *n*. This construction prevents the escape of gases, which is always disagreeable and deleterious; it gives solidity to the covering, and enables it to be manipulated with facility, and an improved draft is a result. *60*

Having thus described my invention, what I claim, and desire to secure by Letters Patent, is—

In combination with an annealing-oven, the *65* covering-plate *i*, the flue *k*, permanently attached thereto, the elbow *n*, and downward-acting flue *o*, substantially as and for the purpose set forth.

LEWIS WILLIAMS.
